UNITED STATES PATENT OFFICE.

CHARLES UEBELMESSER, OF NEW YORK, N. Y.

STEAM-ENGINE-CYLINDER PISTON.

Application filed March 21, 1925. Serial No. 17,204.

As is well known in the prior state of the art, the compression in a steam cylinder incidental to the return stroke of the piston involves a loss of power, and particularly so 5 in the uniflow type of engine; and hence the object of my invention is, primarily, to provide means that will automatically relieve excessive compression between the cylinder head and the piston during the so-called 10 compression stroke. To this end my invention consists in the specific construction, combination and arrangement of piston parts herein described and claimed,—a distinctive feature being the provision of twin 15 relief valves therein actuated simultaneously by a common duplex rocker shaft, all as hereinafter fully set forth.

In the accompanying drawings I illustrate a practical embodiment of the essential 20 features of my invention in a piston of the character designated, although I do not limit myself to the identical form and construction of parts and appurtenances shown by way of exemplification, since changes 25 may be made in minor details and equivalent mechanical expedients resorted to, with like results, and without departing from the spirit and intent of my invention in this respect.

30 With this understanding:—

Fig. 1, represents a side elevation of a piston made in accordance with my invention;

35 Fig. 2, is a longitudinal section thereof, taken upon plane of line 2—2, Fig. 4;

Fig. 3, is an end view of the piston shown in Fig. 1, looking in the direction of the arrow 3, Fig. 1;

40 Fig. 4, is a transverse section of the piston taken upon plane of line 4—4, Fig. 2;

Fig. 5, is a side elevation of one of the valve stem bushings;

Fig. 6, is an end elevation thereof;

45 Fig. 7, is a side elevation of one of the valves;

Fig. 8, is an end elevation thereof;

Fig. 9, is a detail view of one of the valve stems;

50 Fig. 10, is an elevation thereof taken at right angles to Fig. 9;

Fig. 11, is a side elevation of the duplex rocker shaft;

Fig. 12, is an end elevation thereof;

55 Fig. 13, is a sectional elevation of a modification of the piston, taken upon plane of line 13—13, Fig. 14;

Fig. 14, is a sectional elevation taken upon plane of line 14—14, Fig. 13.

The shell of the piston P, is made in two parts, united medially and integrally by 60 screw bolts b, b, as indicated by dotted lines in Fig. 1, of the drawings, or by any other equivalent mechanical expedient. Mounted in a suitable bearing b', positioned medially between the two said halves of the piston shell, is a rocker shaft R, formed with a wrist pin r, at each extremity, said wrist pins r, r, being relatively positioned at right angles to each other, as shown more particularly in Figs. 11 and 12, of the drawings. 65 Slide bearings r', r', fit on said wrist pins r, r, and these slide bearings r', r', fit in transverse recesses s, s, of the cross heads s', s', of the valve stems S, S, the other extremities of said valve stems carrying the valves V, V. In the arrangement shown in the first ten figures of the drawings the outer extremities of the valve stems S, S, are screw threaded for engagement with the valves V, V, whereas in the modification shown in 70 the last two figures of the drawings said valves V, V, form an integral part of the valve stems S, S, as shown in Fig. 13. In either case the valves are connected and controlled simultaneously by the duplex rocker 75 shaft R.

The valves V, V, are essentially cylindrical in type and function, reciprocatable in cylindrical seats p, p, in the piston shell P, and being formed with pressure relief ducts v, 80 v, which, when the valve is in open position as shown at the right hand side of Figs. 2 and 13, admit of communication through the valve between that end of the valve cylinder and the central relief area P', in the piston 85 P, thereby relieving the compression.

Thus constructed and arranged the valves are absolutely noiseless in operation, and are shifted simultaneously by the compression through the medium of the rocker shaft R, 90 in such manner that the opening of one valve closes the other, and vice versa.

The operation of shifting the valves is rendered gradual and uniform, and all impact or abrupt change of motion obviated 105 by the rock shaft R, acting through the medium of its wrist pins r, r, fitting respectively in the slide bearings r', r', in the transverse recesses s, s, of the cross heads s', s', on the valve stems S, said wrist pins travelling 110 each in the arc of a circle as related to the axis of the rock shaft, and being offset as

related to each other as will be understood by reference more particularly to Figs. 11 and 12, of the drawings, thereby avoiding dead centre by counterbalancing each other in this respect.

What I claim as my invention and desire to secure by Letters Patent, is:—

In a steam engine piston of the character designated, the combination of twin compression relief valves the stems of which

are formed with recessed cross heads, slide bearings fitting in said recessed cross heads, and a rock shaft formed with offset wrist pins fitting in said slide bearings and arranged to shift said relief valves to alternately open one valve and close the other simultaneously, and vice-versa, as and for the purpose set forth.

CHARLES UEBELMESSER.
